UPHOLSTERY CONSTRUCTION

Albert M. Bank, Jersey City, N. J., assignor to
Sylvia Bank, Jersey City, N. J.

Application June 19, 1935, Serial No. 27,295

21 Claims. (Cl. 155—179)

This invention relates to upholstery construction. It is particularly directed to a cushion seat or back for chairs, sofas or the like upholstered furniture.

5 An object of this invention is to provide in upholstery construction of the character described wherein a one piece webbing is attached to the frame, highly improved means for resiliently supporting the webbing, including means 10 for positioning the foundation springs on the webbing.

A further object of this invention is to provide upholstery construction of the character described having means for supporting the webbing and foundation springs including members attached directly to the upholstery frame and being resiliently supported by the frame.

A still further object of this invention is to provide a compact, rugged and durable upholstery construction of the character described, comprising comparatively few and simple parts, which shall be relatively inexpensive to manufacture, and withal practical and efficient to a high degree.

25 Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible embodiments 35 of this invention,

Fig. 1 is an elevational, cross-sectional view of a chair embodying the invention;

Fig. 2 is a cross-sectional view taken on line 2—2 of Fig. 1;

40 Fig. 3 is a cross-sectional view taken on line 3—3 of Fig. 1;

Fig. 4 is a partial, top plan view showing the bottom convolution of a foundation spring engaged with the supporting device;

45 Fig. 5 is an elevational cross-sectional view of the seat of a chair, illustrating a modified form of the invention;

Fig. 6 is a detail of large view of the right end of Fig. 5, and Fig. 7 is an enlarged detailed view 50 of the right end of Fig. 1.

Referring now in detail to the drawing, 10 designates a chair embodying the invention, having legs 11, a seat frame 12 and a back frame 13. The seat frame has a front wall 13, a rear wall 14, and side walls 15. Attached to the un-

derside of the frame 12 by tacks, nails or other fastening devices, is a one piece webbing 17. Contacting the underside of the webbing 17 are a plurality of substantially parallel elongated supporting members 18, running from rear to front, and preferably made somewhat flexible, or non-rigid and having apertured swaged end portions 19 attached directly to the lower edges of the front and rear walls, as by nails 20 or in any other suitable manner. For the purpose of 10 illustration, three members 18 are shown in the drawing, it being understood, however, that any suitable number of such members may be provided, depending upon the width of the seat. Each of the members 18 is formed adjacent the 15 ends thereof, with upwardly extending humped or looped portions 21 extending through openings in the webbing, each receiving a washer 22 contacting the underside of said webbing.

For the purpose hereinafter more fully explained, each member 18 is furthermore formed between the portions 21, with a plurality of pairs of spaced humped, looped or offset portions 23 likewise extending through openings in the webbing and receiving washers 24 contacting the 25 underside of the webbing.

Fixed to the front and rear walls 13 and 14 of the frame 12 and aligned with each member 18 is a pair of angle shaped brackets 26, each having a horizontal arm 27 engaging the top of the frame 30 wall, and a vertical arm 28 engaging the inner surface of said frame wall. The arms 27 and 28 may be swaged or flattened and formed with openings receiving nails, screws or other fastening means for attaching the brackets 26 to the 35 frame walls. Interconnecting the arms 27 and 28 of each bracket 26 is a loop 30. Interconnecting each humped portion 21 with the loop 30 of bracket 26 adjacent thereto, is a coil tension spring 31 having hooks at the ends thereof receiving said humped portion and loop.

Mounted on the webbing 17, above each member 18, are a plurality of foundation springs 34 preferably of greater diameter at the ends and gradually decreasing in diameter towards the 45 middle. The bottom convolution 35 of each foundation spring is threaded through a pair of humped portions 23 of member 18. In the drawing, there is shown for the purpose of illustration, three pairs of humped portions 23 on 50 each supporting member 18 and three foundation springs located over each supporting member, and in engagement with the three pairs of humped portions 23 thereof, it being understood, however, that the members 18 may be provided 55

with any suitable number of pairs of humped portions, and the seat may be provided with a corresponding number of foundation springs depending upon the width of the seat and the desired closeness of the foundation springs. The bottom convolution 35 of each spring 34 may be engaged with the humped portions 23 by first inserting the end of said convolution in one of the humped portions and rotating the spring until said end enters the other humped portion.

When the chair 10 is in use the second convolutions 35a, from the bottom, of the foundation springs 34, which are of less diameter than the bottom convolutions, often strike the webbing as said springs are compressed. To prevent said convolutions from wearing out the webbing at the points of contact, the members 18 are formed with pairs of spaced downwardly offset, humped or looped portions 23a disposed inwardly of offset portions 23 and directly beneath said points of contact so that the webbing will not be pressed, at said points of contact, against said members.

To prevent the members 18 from becoming unfastened from the frame when weight is applied to the chair 10, there is attached to the inner surfaces of the front and rear walls 13, 14 of said frame, a pair of anchoring members 25 aligned with each member 18. The members 25 each comprises a plate having an opening at the upper end receiving a nail, screw or other fastening device for fixing said plate to the frame. Said members 25 have downwardly extending portions 25a formed with vertical slots 25a through which the ends of said members pass. Said portions 25a contact the flattened or swaged ends 19 of said members 18 to aid in preventing the members 18 from pulling away from the frame at the anchored ends thereof.

The upper convolutions of the springs 34 may be tied together by the usual tie cords 36, said tie cords being tied to the loops 30 at the front and rear of the frame, and attached to the side walls 15 of the frame in any suitable manner.

It will now be understood that the springs 31 provide a resilient support for the members 18. The weight on the spring 34 is taken up by said springs 31 to aid in preventing ripping of the margin of the webbing away from the frame.

The chair back is constructed in substantially the same manner as the seat, said back likewise being provided with a webbing 17, supporting members 18, foundation springs 34 and coil tension springs 31 interconnecting the members 18 with the forward edges of the frame. The supporting members 18 for the webbing of the chair back are likewise provided with humped portions 23 receiving the rear convolutions of the springs 34 to prevent shifting of said springs. The humped portions thus anchor the foundation springs and obviate the necessity for clips or other fastening members for the bottom ends of the foundation springs.

The members 18 of the chair back may also be formed with offset portions 23a, to prevent grinding or wearing of the webbing at the points where the second convolutions of the foundation springs contact the webbing. The ends of members 18 may pierce the webbing and be fastened to the inner surfaces of the top and bottom walls of the chair back frame.

In Fig. 5 there is shown a modified form of the invention. In said figure, the frame 12a is likewise shown as provided with a one piece webbing 17a attached at the margin thereof to the under-

side of the frame by tacks or any other suitable fastening means. Contacting the underside of the webbing 17a are a plurality of supporting members 18a, preferably made of round wire stock, and each having a forward end extending through the webbing and attached to the inner surface of the front wall of the frame as at 40, by nails or other suitable fastening devices. Adjacent to the attached end 40 thereof each member 18a has a looped portion 41. The opposite end of each member 18a is not attached directly to the rear wall of the frame, but terminates short thereof in a loop 42. Each member 18a is formed with an upwardly extending humped portion 44 spaced from the loop 41 by a distance equal to the diameter of the bottom convolution of one of the foundation springs 45 mounted on the webbing, as will appear hereinafter. Each member 18a is furthermore formed with a plurality of pairs of spaced upwardly extending humped or looped portions 46 extending through openings in the webbing. Washers 47 receiving the humped portions 44 and 46 contact the underside of the webbing. The foundation springs 45 located at the front of the frame 12a have the lower convolution 48 thereof received within the loops 41 and humped portions 44. Mounted on the webbing 17a and located above each member 18a, are a plurality of foundation springs having the lower convolutions thereof received within pairs of humped portions 46. Brackets 26 are attached to the upper edges of the front and rear walls of the frame. Interconnecting the loops 42 at the rear ends of the members 18a with the brackets 26 on the rear wall of the frame 12a are coil tension springs 50. The upper convolutions of the foundation springs 45 may be interconnected by tie cords 51 fastened likewise to the brackets 26 and side walls of the frame.

Members 18a may also be provided with downwardly offset portions 46a to prevent wearing away of the webbing where the second convolutions from the bottom of the foundation springs contact the webbing. Said members 18a may be further anchored to the front wall of the frame 45 by anchoring members or plates 54 aligned with said members and fixed to the under edges of said front walls. Said plates have slots receiving the adjacent ends of said members 18a as shown in Fig. 5 of the drawing.

It will now be understood that the members 18a are attached directly to the frame only at the front. The springs 45 located at the front of the frame 12a are disposed closely adjacent to the front wall of the frame and are substantially greater in height, normally, than the front wall of said frame, forming what is known in the art as a spring edge seat.

In the construction of Figs. 1 and 2, the foundation springs at the front of the seat are spaced from the front wall 13 of the frame and are substantially of the same height as said front wall forming what is known in the art as a hard edge seat. The invention may thus be embodied either in a soft edge or hard edge seat of a chair or sofa. It will be understood that the structure of Fig. 5, is shown for the purpose of illustration, only, as incorporated, into a chair seat, and may be readily incorporated into a chair back.

It will thus be seen that there is provided a device in which the several objects of this invention are achieved and which is well adapted to meet the conditions of practical use.

As various possible embodiments might be

made of the above invention and as various changes might be made in the embodiments set forth, it is to be understood that all matter herein set forth or shown in the accompanying drawing is to be interpreted as illustrative and not in a limiting sense.

Having thus described my invention, I claim as new and desire to secure by Letters Patent:

1. In upholstery construction, a frame, a one piece webbing attached thereto, a member contacting the underside of said webbing and attached at the ends thereof to said frame, and coil tension springs located above the webbing interconnecting intermediate portions of said member with portions of said frame above the webbing.

2. In upholstery construction, a frame, a one piece webbing attached thereto, a member contacting the underside of said webbing and attached at the ends thereof to said frame, coil tension springs interconnecting intermediate portions of said member with said frame, said members having pairs of humped portions extending through said webbing, and a plurality of foundation springs on said webbing, aligned with each member, each spring having an end convolution thereof threaded through a pair of humped portions.

3. In upholstery construction, a frame, webbing attached at its margin directly to said frame, a plurality of parallel elongated members contacting the underside of said webbing, one end of each member being attached directly to said frame, resilient means disposed above the webbing connecting the other end of each member with said frame, each member having a plurality of intermediate integral offset portions extending through said webbing, foundation springs on said webbing each having an end convolution thereof engaging an offset portion.

4. In upholstery construction, a frame, a one piece webbing attached thereto, a member contacting the underside of said webbing, means for connecting said member to said frame, a plurality of foundation springs on said webbing and directly over said member, said springs decreasing in diameter from both ends toward the center thereof, said member having pairs of portions offset away from said webbing at the points where the second convolutions from the bottom of said springs contact said webbing when the said springs are compressed, to prevent said second convolutions from pressing said webbing directly against said member.

5. In upholstery construction, a frame, a webbing attached at the margin thereof to said frame, a plurality of members contacting the underside of said webbing, means for connecting said members to said frame, said members having offset portions extending through said webbing, and foundation springs on said webbing engaging said offset portions, said members having downwardly offset portions at the points where the second convolutions from the bottom of said foundation springs contact said webbing when said springs are compressed to prevent said second convolutions from pressing said webbing directly against said members.

6. In upholstery construction, a frame, a webbing attached at the margin thereof to said frame, a plurality of members contacting the underside of said webbing, means for connecting said members to said frame, said members having offset portions extending through said web-

bing, foundation springs on said webbing engaging said offset portions, said members having downwardly offset portions at the points where the second convolutions from the bottom of said foundation springs contact said webbing when said springs are compressed to prevent said second convolutions from pressing said webbing directly against said members, and means for anchoring said members to said frame, comprising anchor plates attached to said frame and receiving adjacent end portions of said members.

7. In upholstery construction, a frame, a one-piece webbing attached at the margin thereof directly thereto, a member contacting the underside of said webbing and attached at the ends thereof directly to said frame, tension means interconnecting an intermediate portion of said member with an upper portion of said frame, said member having portions extending through said webbing, and a foundation spring on said webbing aligned with said member and having an end convolution thereof engaging one or more of said portions.

8. In upholstery construction, a frame, webbing attached at its margin to said frame, a member made of round wire stock disposed beneath and contacting said webbing and having the ends thereof attached directly to said frame, said member having a pair of integral offset portions passing through openings in said webbing, and a pair of coil tension springs having the upper ends thereof attached to said frame and the lower ends thereof engaging said offset portions.

9. In upholstery construction, a frame, webbing attached at its margin to said frame, a member made of round wire stock disposed beneath and contacting said webbing and having the ends thereof attached directly to said frame, said member having a pair of integral offset portions passing through openings in said webbing, a pair of coil tension springs having the upper ends thereof attached to said frame and the lower ends thereof engaging said offset portions, a plurality of foundation springs on said webbing and said member having offset portions extending through the webbing and engaging the lowermost convolutions of said foundation springs.

10. In upholstery construction, a frame, a webbing attached at the margin thereof to said frame, a plurality of coil foundation springs on said webbing, each having convolutions of gradually decreasing diameter, and an elongated member contacting the underside of the webbing and having an offset portion extending through the webbing, tension means connecting said offset portion to said frame, said member having additional offset portions extending through the webbing and engaging the lowermost convolutions of said foundation springs.

11. In upholstery construction, a frame, a webbing attached at the margin thereof to said frame, a plurality of coil foundation springs on said webbing, each having convolutions of gradually decreasing diameter, and an elongated member contacting the underside of the webbing and having an offset portion extending through the webbing, tension means connecting said offset portion to said frame, said member having additional offset portions extending through the webbing and engaging the lowermost convolutions of said foundation springs, and said member furthermore having portions offset away from the webbing and located in such positions as to prevent portions of said foundation springs from

- pressing said webbing directly against said member.
12. In upholstery construction, a frame having upstanding walls, webbing secured at its margin directly to the frame, adjacent the lower edge of the latter, foundation springs on said webbing, a member secured to the underside of a wall of the frame and having a portion extending inwardly of said wall and formed with an opening, and a member attached to said wall above the webbing and extending through said opening and through said webbing, and having a portion contacting the underside of the webbing and being connected to an opposite wall of said frame.
13. In upholstery construction, a frame, a webbing attached to the margin thereof directly to said frame, an elongated member contacting the underside of said webbing, means above the webbing connecting said member to said frame, for exerting an upward tension on said member, said member having offset portions extending through said webbing, and foundation springs on said webbing engaging said offset portions.
14. In upholstery construction, a frame, a webbing attached to the margin thereof directly to said frame, an elongated member contacting the underside of said webbing, means above the webbing connecting said member to said frame, for exerting an upward tension on said member, said member having offset portions extending through said webbing, foundation springs on said webbing engaging said offset portions, and washers receiving said offset portions and disposed between said webbing and member.
15. In upholstery construction, a frame, a one piece webbing attached at the margin thereof directly to said frame, a plurality of members contacting the underside of said frame, and having end portions fixed to said frame, resilient means disposed above said webbing and interconnecting said members with said frame for pulling upwardly on said members, a plurality of foundation springs on said webbing, and means integrally formed with said members for engaging the adjacent convolutions of said springs.
16. In upholstery construction, a frame having a top and bottom edge, a one piece webbing attached to the bottom edge of said frame, a member contacting the underside of said webbing and having an end attached to the bottom edge of said frame, tension means connecting a portion of said member spaced from said end to the top edge of said frame, foundation springs on said webbing, and a member attached to said frame adjacent the bottom edge thereof and having an opening receiving said first named member therethrough.
17. In upholstery construction, a frame, a one piece textile fabric webbing attached at its margin directly to the underedges of said frame, a member contacting the underside of said webbing and attached at an end thereof directly to said frame, and flexible means located above the webbing interconnecting a portion of said member spaced from said frame with a portion of the frame above the webbing.
18. In upholstery construction, a frame, a one-piece textile fabric webbing attached at its margin directly to the underedge of said frame, an elongated member contacting the underside of said webbing and having an end attached directly to said frame, and means located above the webbing interconnecting a portion of said member spaced from said frame with an upper portion of said frame.
19. In upholstery construction, a frame, a one-piece textile fabric webbing attached at its margin directly to the lower edge of said frame, an elongated member contacting the underside of said webbing attached at one end thereof directly to a wall of said frame and extending at right angles to said wall, the other end of said member being located at a point spaced from the walls of said frame and at an intermediate portion of said webbing, and means for connecting said other end of said member to an upper portion of said frame.
20. Upholstery construction comprising a frame, a yieldable webbing secured along its marginal edges to said frame and normally disposed in a single flat plane, a supporting spring-steel rod directly attached at its ends to opposite walls of the frame, said rod being normally disposed in a plane parallel to the webbing and located directly under and in contact with said webbing, said rod being longitudinally yieldable whereby the rod will bow downwardly co-extensively with the webbing when weight is placed upon the latter and then return to normal position when relieved of said weight, and a foundation spring seated on the webbing directly above the rod whereby both the webbing and the rod support said spring, said rod being provided with a pair of spaced eyes projecting upwardly through the webbing for receiving the lower convolution of the spring.
21. Upholstery construction comprising the combination with a frame, and a yieldable webbing of vegetable fibre secured along its marginal edges to said frame and normally disposed in a single flat plane, of an attachment therefor comprising a one-piece supporting metallic rod directly attached at its ends to the lower edges of the opposite walls of the frame, said rod being normally disposed in a plane parallel to the webbing and located wholly and directly under and in contact with said webbing, said rod being longitudinally yieldable whereby the rod will bow downwardly co-extensively with the webbing when weight is placed upon the latter, and a supplement attaching means for the rod comprising a hanger secured to the frame and having an eye extending below the webbing for receiving the rod.

ALBERT M. BANK.
